MAGNETIC DATA-STORAGE STRIP CANISTER

Melvin H. Best, Pasadena, Merton C. Leinberger, Inglewood, and Norman J. Schweitzer, Los Angeles, Calif., assignors to The National Cash Register Company, Dayton, Ohio, a corporation of Maryland

Filed July 11, 1962, Ser. No. 70,889

Term of patent 14 years

(Cl. D26—5)

Fig. 3

Fig. 4

Fig. 5

FIG. 1 is a front perspective view of a magnetic data-storage strip canister, showing our design.
FIG. 2 is a rear perspective view of the same.
FIG. 3 is a rear elevation view of the same.
FIG. 4 is a left side elevation view of the same.
FIG. 5 is a top plan view of the same.

We claim:

The ornamental design for a magnetic data-storage strip canister, substantially as shown.
